PILL DISPENSER

Raymond Beaumann, Les Bois, Switzerland, assignor to Ebauches S.A., Neuchatel, Switzerland

Filed Nov. 17, 1960, Ser. No. 62,875

Claims priority, application Switzerland May 27, 1960

Term of patent 14 years

(Cl. D52—2)

FIG. 1

FIG. 2

The dominant features of the design reside in the portions shown in full lines. The undisclosed side of the article is substantially the same in appearance as the side shown.

I claim:

The ornamental design for a pill dispenser, substantially as shown and described.
